CASE SHIFTING MECHANISM AND REPEAT
TYPING MECHANISM FOR POWER-OPER-
ATED TYPEWRITERS AND LIKE MA-
CHINESWilliam H. Kupper, West Hartford, Conn., as-
signor to Royal Typewriter Company, Inc., New
York, N. Y., a corporation of New York

Application December 16, 1949, Serial No. 133,322

31 Claims. (Cl. 197—17)

1

This invention relates to power operated type-
writers or like machines and more particularly
to case shifting mechanism and repeat typing
mechanism for such machines. Some power
operated typewriters or like machines now
known include power operating mechanism for
shifting a case shiftable element and holding it
in shifted position and power operating mecha-
nism responsive to manipulation of a repeat key
for effecting automatically repeated typing 10
strokes of a typing member.

An object of the present invention is to pro-
vide a power operated typewriter or like ma-
chine including power operated case shifting
and repeat typing mechanism operable under
the conjoint control of a single manipulatable
element e. g., a key, for shifting the case shift-
able element and automatically effecting repeat-
ed typing operations of one of the typing mem-
bers. Constructions embodying the invention
are especially suited for shifting a typewriter
case shiftable element and effecting automatic-
ally repeated operation of a type bar or the
like having an underscoring character correlated
to the other parts so as to be effective for typ-
ing when the shiftable element is in shifted pos-
ition.

Another object of the invention is to provide
an improved power operated case shifting mech-
anism for typewriters or like machines.

Another object of the invention is to provide
an improved arrangement of connections for
transmitting a cushioned or shockless drive from
a power mechanism to the case shiftable ele-
ment of a typewriter or like machine.

Another object of the invention is to provide a
power operated case shifting mechanism includ-
ing a novel and improved arrangement for re-
taining the case shiftable element in shifted po-
sition after the drive connections between the
case shiftable element and a continuously op-
erating driving means have been disabled.

A further object of the invention is to provide
a novel and improved mechanism for effecting
automatically repeated typing operations of a
type bar or similar member.

Other objects of the invention will become
apparent from a reading of the following de-
scription, the appended claims, and the ac-
companying drawings in which:

Figures 1 to 5 show one form of mechanism em-
bodying the invention, and more specifically;

Figure 1 is a view, partly in elevation and part-
ly in vertical section, fore-and-aft of a typewriter
embodying the invention, showing only some of

2

the conventional or standard typewriter parts in
order to illustrate the application of mechanism
embodying the invention to a typewriter con-
struction, the parts being shown in their normal
or inactive positions;

Figure 2 is a fragmentary view, partly in sec-
tion and partly in elevation, showing a cushion
lever device and associated elements with the
parts shown in their activated positions, that is,
the positions they occupy when a case shift ele-
ment is in upper case position;

Figure 3 is a fragmentary view, partly in ver-
tical section, fore-and-aft of the machine, with
parts shown in elevation in the positions they
occupy when the case shift element is in upper
case position;

Figure 4 is an enlarged substantially horizontal
sectional view on the irregular line 4—4 of Figure
3; and

Figure 5 is an enlarged detail fragmentary sec-
tional view on the line 5—5 of Figure 3;

Figures 6 to 9, inclusive, show a case shift mech-
anism generally similar to the mechanism shown
in Figures 1 to 5, inclusive, and also illustrate
more fully a repeat typing mechanism only a
part of which is shown in Figure 1, and more
particularly;

Figure 6 is a view similar to Figure 1, but show-
ing in combination the case shifting mechanism
and the repeat typing mechanism with the parts
shown in their normal or inactive positions;

Figure 7 is a fragmentary view, partly in ver-
tical fore-and-aft section, of a key operated
mechanism shown in Figure 6 but with the parts
shown in their actuated positions;

Figure 8 is a detail perspective view of a key or
the like member for operating both the case shift-
ing mechanism and the repeat typing mechanism;
and

Figure 9 is a detail horizontal section on the
line 9—9 of Figure 6.

Figures 10 to 12, inclusive, show a further modi-
fied construction embodying both a case shift-
ing mechanism and a repeat typing mechanism,
and more particularly;

Figure 10 is a view similar to Figure 6 but
showing the modified construction with the parts
in their normal or inactive positions;

Figure 11 is a fragmentary vertical sectional
view fore-and-aft of the machine, showing key
mechanism illustrated in Figure 10, but with the
parts in their active positions; and

Figure 12 is a perspective, skeletonized view of
the mechanism shown in Figures 10 and 11, with
some parts omitted.

The invention may be embodied in typewriters or like machines of various kinds. For the purposes of illustration, the invention is shown as being embodied in an office type typewriter having, except for the power generating and transmitting mechanism to be described, many features in common with the well known Royal Standard typewriter. The drawings show only enough of the standard or known typewriter construction to assist in illustrating the manner in which mechanism embodying the invention may be coordinated with other parts of a typewriter construction.

The embodiment of the invention shown in Figures 1 to 5, inclusive, will be described first. The known construction illustrated in these figures includes a main frame A on which a carriage B equipped with a platen C is mounted for letter spacing and return movements by means of a top rail 1 secured to the carriage, and rolling upon balls 2, which in turn are adapted to roll on a frame-mounted bottom rail or track 3.

The carriage may be driven toward the left, that is, in the letter-spacing direction, by any suitable mechanism, for example, by a spring barrel and draw band (not shown) of known or suitable construction. Carriage returning mechanism may be of the kind disclosed in the co-pending application of Henry J. Hart, Serial No. 21,476, filed April 16, 1949, now U. S. Patent No. 2,567,937, or of other suitable construction, preferably power-operated.

A case shift segment element 4 is mounted to shift vertically on the frame A by a construction not shown but which may be of a well known form. Mechanism for shifting the segment includes a link 5 pivoted as at 6 to the segment and pivoted as at 7 to an arm 8 mounted on a shaft 9 extending lengthwise of the typewriter and mounted in any suitable manner at its opposite ends on the frame A. The arm 8 is formed with an extension 10 provided with a hook portion 11 to which is connected the front end of a counterbalancing spring 12 the rear end of which is anchored on a fixed bracket 13. As in the standard Royal office typewriter, the shaft 9 may be equipped at both ends with a rock arm 8, and both of the arms 8 may be associated with links 5 and counterbalancing springs 12.

The counterbalancing springs 12 normally maintain the type bar segment 4 in its upper position with respect to the frame, which is its lower case position for the purposes of typing. In order to shift the segment 4 downwardly to its upper case position, the shaft 9 is rocked counterclockwise by mechanism to be described. The downward movement of the case shift element 4 is cushioned by springs 14 and nuts 15 mounted on studs 16 carried by opposite sides of the segment and being arranged to move vertically through apertured fixed frame parts 17 as shown in Figure 3. Movement of the segment 4 upwardly to its lower case position is cushioned by springs 18 and nuts 19 mounted on the studs 16 below the fixed frame parts 17.

In order to retain the segment 4 in its raised, or lower case position so as to prevent accidental displacement which might be caused by vibration incident to operation of the machine, a segment lock or anti-vibration device, generally designated 20, is provided. The device 20 comprises a cushion spring 21 carried by a mounting member 22 secured to the segment 4 by a screw 23, and a shift lock or dog 24 pivoted on

the frame at 25 and normally engaging the bottom of the spring 21.

The segment 4 is provided with the usual arcuate pivot wire 26 on which the usual complement of typing members, one only of which is shown at 27 as a front strike type bar, is pivoted. The type bar 27, shown, has a lower case typing character 27^a and an upper case typing character 27^b which, in the form shown, is an under-scoring or underlining character.

In general, the construction described so far is of a known kind and does not in itself constitute the present invention. The invention resides in other parts to be described, and the combinations of such other parts with each other and with the parts described above.

Broadly considered, counterclockwise rocking of the shaft 9 and consequent shifting of the segment 4 are effected by power-driven means, generally designated D, which may be made effective by depression of a manually operable shift key E. Power is transmitted from the power-driven means D through a train of driving connections F. The construction and arrangement of the parts is such that, upon depression of the shift key E, a quickly generated power impulse is transmitted through a cushion device embodied in the train of connections F, to the shaft 9 so as to rock the latter and operate the associated shift mechanism in the manner previously described.

The power-driven mechanism D is generally similar to but embodies improvements in mechanism disclosed in the co-pending application of William H. Kupper, Serial No. 6,066, filed February 3, 1948, now U. S. Patent No. 2,567,945. It includes a driving element, which operates continuously, and controllable driving connections, which normally are inoperative or ineffective, but which may be conditioned by the operator to effect operative driving connection between the continuously moving driving member and the train of connections F. The driver preferably is constituted by a rotatable continuously driven member, more particularly a toothed snatch roll or bar 28, which may be of known form, and which is adapted to be driven in the direction of the arrow a in the Figure 1 by any suitable means, but preferably by an electric motor (not shown).

The means for transmitting drive from the driver 28 to the connections F includes an actuator 29 which extends fore and aft of the typewriter and above the member 28. The actuator 29 is pivoted as at 30 to a lever 31 at a point offset relatively to the pivotal mounting 32 of the lever on a fixed frame cross bar 33. The actuator has a forwardly extending part 34 projecting under an abutment or guide plate 35 mounted on the frame A, to extend parallel to the snatch roll 28. A spring 36, interposed between the front end of the actuator 29 and an anchor plate 31, yieldably urges the actuator to rock clockwise, and thus normally maintains the actuator in the position shown in Figure 1 with its front end part 34 bearing against the abutment or guide plate 35. Another abutment 38 is disposed below the abutment 35, and is slotted to receive and guide the lower extremity of the actuator part 34 for sliding movements. The lever 31 normally is held in its inactive position, shown in Figure 1, by a returning spring 39 interposed between an ear 40 on the lever and an anchor plate 41 mounted on the fixed cross bar 33 by screws, one of which is shown at 42. The lever 31 has a stop

part 43 engageable with a fixed stop strip 44 for limiting the returning movement of the lever under the urge of the spring 39.

In order to apply a power impulse to the train of driving connections F, the actuator 29 is operatively but indirectly connected to the driving member 28, the actuator itself never engaging the driving member. Mechanism for bringing out this operative connection includes an interponent pawl element 45, pivotally mounted as at 46 on the actuator. A spring 47, anchored to the actuator 29 and connected to the pawl 45, biases or urges the latter to rock clockwise so as to move its double toothed nose into engagement with the snatch roll 28. Normally, the pawl is maintained out of engagement with the snatch roll by the restraining action of a control element or trigger 48 which is pivotally mounted as at 49 on the actuator 29. In the normal position of the trigger, its rear end engages a holding surface 50 on the pawl so as to prevent the spring 47 from rocking the pawl 45 into drive-transmitting engagement with the driving member 28. The pawl 45 is formed with an inclined resetter cam face 51 which is located just below the holding surface 50, and which is acted upon by the trigger for rocking the pawl counterclockwise, and thus resetting it in normal, inoperative position.

Operator controlled means for bringing about operative driving connection between the driver 28 and the actuator 29 includes the manually operable shift key E pivoted as at 52 on the frame A. As is customary, the shift key structure E includes two key lever parts at opposite sides of the machine, only the one of such parts at the left of the machine being shown, and designated 53. The key lever part 53 is equipped with a shift key lock lever 54 to be described later. The shift key lever part at the right of the machine is similar to the lever part 53 shown, but need not be provided with a locking lever corresponding to the lever 54. Both of the shift key lever parts 53 are joined by a rod 55 extending transversely across the front of the machine so as to form a solid unit shift key structure E. Both levers 53 have rearward extensions 56 pivotally mounted on the frame pivot 52.

The key structure E has a rearward projection 57 and an upward projection 58 disposed behind an arm 59 of an operating lever 60, pivoted as at 61 on a frame-mounted cross bar 62. The lever 60 has another arm 63 on which a limber dog or flipper 64 is pivoted at 65. A spring 66 urges the limber dog 64 to rock clockwise to yieldably retain it in its normal position of rest against a limit stop 67 on the lever arm 63. The dog 64 can swing counterclockwise from the position shown in Figure 1, but cannot move clockwise from this position. A returning spring 68, interposed between the key structure E and a short arm 69 on the lever 60, yieldably holds the lever 60 and the key structure E in their normal positions. When the parts are in their normal positions the spring 68 holds the lever 60 so that the lower end of the limber dog 64 overlies a contact ear 70 on the actuator 29, and holds the key E so that it bears upwardly against a cushion stop 71.

In operation, when the shift key E is depressed, the lever 60 is rocked clockwise to cause the flipper 64 to push the actuator 29 downwardly to an initial extent sufficient to bring the trigger 48 into engagement with the abutment 38. This causes the trigger to be rocked clockwise about

its pivot 49, so as to release the pawl 45, which is then moved by the spring 47 into engagement with the snatch roll 28. The snatch roll then drives the assembly constituted by the pawl 45, actuator 29 and trigger 48 forwardly as a unit so as to operate the case shift mechanism through the train of connections F in a manner herein-after described. When the pawl 45 is cast off from engagement with the snatch roll 28, the spring 36 lifts the actuator 29 to bring the trigger 48 into engagement with the upper, trigger-resetting abutment 35. This causes the trigger 48 to be rocked counterclockwise, so as to move its rear end against the resetting cam face 51 of the pawl 45, thereby restoring the latter to its inactive position.

Means are provided for adjusting or varying the amount of driving impulse generated by the power mechanism D. This variation or adjustment is effected by variably limiting the extent to which the teeth on the actuator pawl nose enter tooth interspaces on the snatch roll 28 under the urge of the spring 47 when the restraint of the trigger 48 on the pawl 45 is discontinued. In the form shown, the actuator 29 is provided with a downwardly extending stop element or finger 72 which is disposed in front of and normally out of contact with a downwardly extending stop part, heel, or finger 73 on the pawl 45. When the pawl 45 is rocked clockwise by the spring 47 so as to move the teeth on the pawl nose into snatch roll tooth interspaces, the pawl stop 73 moves toward the actuator stop 72, which may be so positioned as to be engaged by the stop 73 to arrest rocking of the pawl 45 before the pawl teeth move to the roots of the snatch roll tooth interspaces. By variably positioning one of the stops 72, 73, e. g., by bending the stop 72 towards or away from the stop 73, the extent to which the pawl teeth enter the tooth interspaces on the snatch roll can be varied. Consequently, the angle through which the snatch roll rotates while in contact with the pawl, which determines the amount of driving of the pawl 45 and actuator 29 by the snatch roll 28, can be varied. Any suitable means or construction may be provided for adjusting one of the stops 72, 73 relatively to the other, but in the preferred construction the stop 72 is formed integrally with the actuator 29 so as to be bendable toward or away from the stop 73.

In typewriters or like machines in which all or some of the instrumentalities to be operated, e. g., type bars, carriage return mechanism, tabulating mechanism, escapement mechanism, back spacing mechanism, as well as case shift mechanism, are operated by power, it may be desirable to provide means for varying collectively the extent of driving of the several actuator pawls corresponding to the pawl 45 and associated with the other mechanism referred to. This may be accomplished by providing a knock-off bar 74 mounted on the main frame so as to extend under the front ends of all of the actuators corresponding to the actuator 29 shown in Figure 1. Any suitable means (not shown), may be provided for adjustably tilting or otherwise variably positioning the knock-off bar 74 so that it will be engaged by the lower ends of the actuators to control the timing of disengagement of the associated actuator pawls from the snatch roll.

The train of connections F is so arranged, constructed, and coordinated with the power mechanism D and case shift mechanism as to sup-

press or cushion the impact or concussion which otherwise would be transmitted abruptly from the power mechanism D to the shift mechanism. Accordingly, undesirable noise and harmful shocks are prevented, and danger of jamming of the machine with resultant damage is eliminated. In the construction shown, a pull link generally designated 75 is pivoted as at 30 to the actuator 29 and is pivoted as at 76 to a cushioned lever device generally designated 77 arranged to operate the shaft 9 for shifting the segment 4. The pull link 75 preferably is constructed so as to permit its being adjusted to different lengths. As shown, the link 75 comprises two joined sections 75^a and 75^b. The section 75^b is formed with a horizontal slot 78 which receives a pin 79 secured to the section 75^a. The section 75^b also is formed with a horizontal slot 80 which receives the shank of a screw 81 having threaded connection to the section 75^a. The section 75^a is formed with a vertical slot 82 in which is disposed the eccentric head of a stud 84 secured to the section 75^b by a nut 85. In order to adjust the length of the link 75, the screw 81 and nut 85 are loosened, and the eccentric stud head 84 is turned to effect relative endwise shifting of the link sections 75^a and 75^b, after which the screw 81 and nut 85 are tightened to lock the link sections in adjusted positions.

The pivot 30, previously referred to, is constituted by a shoulder stud passing through the lever 31, the rear end of the actuator 29 and the front end of the link section 75^b, the stud being threaded to the rear end of a shift mechanism locking bar 86. The link 75 and bar 86 oscillate together, and conjointly constitute a case shift actuator and retainer, the retaining operation of which will be described later.

When the interponent 45 and actuator 29 are moved forwardly by the snatch roll 28 in the manner previously described, the link 75 also will be moved forwardly. This motion of the link 75 is utilized for transmitting force through the cushion lever device, generally designated 77, so as to rock the shaft 9 counterclockwise and move the segment 4 downwardly through the operation of the arms 8 and links 5, previously referred to. The cushion lever device 77 includes a lever arm 88 which is fast on the shaft 9 and which is formed with a rearwardly extending part 89 provided with a plurality of spring seats 90. Another lever arm 91, pivoted as at 92 on the arm 88, is provided with a pin projection 93 which is movable in a slot 94 in the lever arm 88, the ends of the slot 94 being engageable by the pin 93 for limiting relative rocking or pivotal movement of the lever arms 88 and 91. A drive-transmitting spring 95 is interposed between the arm 91 and one of the spring seats 90 which may be selected for varying the effect of the spring in urging the lever arms 91 and 88 to rock toward each other.

The pivot 76, previously referred to, is constituted by a pin secured to the lever arm 91 and projecting into a horizontally extending slot 96 in the rear end of the pull link 75. Normally when the parts are in the positions shown in Figure 1 with the segment 4 in its raised, or lower case position, the pin 76 is at the front end of the slot 96.

In operation, when the shift key structure E is depressed, the interponent 45 will become engaged with the snatch roll 28, and the interponent and its associated actuator 29 will be driven forwardly

in the manner previously described. The forward driving of the actuator 29 will impart a sudden or quickly applied impulse to move the pull link 75 forwardly. The sudden forward movement of the pull link 75 will first take up the lost motion at the pivot 76, and when the rear end of the slot 96 engages the pivot pin, the lever arm 91 will be rocked counterclockwise. This will exert a pull on the cushioning, force-transmitting spring 95, resulting in rocking the lever arm 88 counterclockwise, with consequent counterclockwise rocking of the shaft 9 and the rock arms 8 so as to pull the links 5 and segment 4 downwardly. During the initial forward movement of the link 75, and prior to rocking of the lever arm 91, the segment locking dog 24 is withdrawn from engagement with the spring abutment 21 by mechanism to be described later.

It is desirable that the segment 4 remain in its lower position on the frame, that is, its upper case position, following its shifting by the mechanism D, as long as the shift key structure E is held depressed. Inasmuch as the interponent 45 is cast off the snatch roll 28, and is then returned to its normal position when the key structure E is held depressed, it is necessary to provide additional mechanism for maintaining the segment 4 in its shifted or upper case position. In mechanism constructed in accordance with the present invention, the locking bar or link 86, previously referred to, extends from the pivot 30 forwardly for cooperation with cooperating locking mechanism disposed near the front of the machine. Preferably, the link 86 is constructed to permit its being adjusted as to length. In the form shown, the link 86 comprises two relatively adjustable sections 86^a and 86^b. The section 86^a has a horizontal slot 97 receiving a pin 98 on the section 86^b, and a horizontal slot 99 receiving a screw 100 threaded to the section 86^b. A vertical slot 101 in the section 86^b receives the eccentric head on a stud 102 secured to the section 86^b by a nut 103. By loosening the screw 100 and nut 103, and turning the stud 102, the desired relative adjustment of the sections 86^a and 86^b may be effected. The sections may then be locked in adjusted position by tightening the screw 100 and nut 103.

As shown in Figure 5, the front end of the bar section 86^a extends alongside the end of the upper abutment 35 previously referred to. The bar section 86^a is provided with guide studs 104 extending respectively above and below the abutment 35, and is formed with a horizontally extending ear 105 which engages the side of the frame A for guiding the bar section 86^a and maintaining it against displacement away from the adjacent end of the abutment 35.

When the parts are in the normal positions shown in Figure 1, an upstanding projection 106 at the front of the bar 86 is positioned under, and in contact with, the substantially flat horizontal surface under the nose of a retaining device comprising a pawl 107 mounted to rock on a fixed frame pivot 108. The pawl nose is formed with a surface 109 inclined to the direction of oscillation of the bar 86 and adapted to engage a similarly inclined surface on the projection 106 when the bar 86 is in its shifted position as shown in Figure 3, the pawl thus tending to maintain the bar 86 releasably in its shifted position. For urging the pawl 107 to the retaining position shown in Figure 3, a spring 110 is interposed between a tail 111 on the pawl and a holding or locking part, as shown a dog 112, pivoted at 113

on a bracket 114 secured to the cross bar 62. The spring 110 urges both the pawl 107 and the dog 112 clockwise. The dog 112 normally is held in the retracted position shown in Figure 1 by engagement of the shift key extension or blocking part 58 with an ear or blocking part 115 on the dog 112.

In operation, when the key E is depressed, the extension 58 retreats from the part 115 of the dog 112, thereby enabling the dog to rock clockwise into the position shown in Figure 3 as soon as the pawl 107 has moved to its Figure 3 position consequent upon sliding of the projection 106 under the pawl 107 and to the left of the pawl inclined surface 109. Thus, when the shift actuator 75, 86 has been moved forwardly by the actuating mechanism D, it will be locked or retained in its shifted position by the pawl 107 the holding tendency of which will be supplemented by the dog 112 when the lower end of the dog engages the pawl and prevents it from rocking counterclockwise to release the projection 106. When the shift key E is released so as to permit its returning spring 68 to raise it, the key extension 58 presses against the ear 115 and rocks the dog 112 clear of the top of the pawl 107, thus releasing the pawl for counterclockwise pivotal movement. The similar inclinations of the pawl nose surface 109 and of the engaging part of the projection 106 on the bar 86 are such that these mutually engageable parts constitute cam means by which the pawl 107 is cammed counterclockwise under the urge of the counterbalancing springs 12, which constantly tend to pull the bar 86 rearwardly and shift the segment 4 to lower case position. Preferably, the lower end of the dog 112 and the top surface of the pawl 107 are notched or cut away so as cooperatively to limit the clockwise movement of the dog 112 when it is rocked to the holding position shown in Figure 3.

As previously stated, it is necessary to retract the anti-vibration dog 24 from its engagement with the spring 21 prior to shifting the segment 4 downwardly to its upper case position. In the form shown in Figures 1 to 5, mechanism for accomplishing this purpose includes an ear 116 extending upwardly from the locking bar section 86^b. A wire link 117 is pivoted as at 118 to the ear 116 and as at 119 to the dog 24. When the locking bar 86 is moved initially forwardly, the link 117 rocks the dog 24 counterclockwise so as to release the segment 4 for its shifting movement which begins later in the cycle after the taking up of the lost motion at the pivotal connection 76. As shown, the link 117 is of a well-known adjustable form.

The embodiment of the invention shown in Figures 1 to 5, inclusive, also comprises mechanism for locking the shift key structure E in its depressed position. The shift key lock lever 54, previously referred to, is pivoted as at 120 on the left-hand shift key lever 53 and is formed with a depending part 121 having spaced stop ears 122 engageable respectively with opposite sides of the key lever 53. A tail 123 on the shift lock key lever 54 projects under the heel 124 of a latching dog 125 pivoted as at 126 on the shift key lever 53. A spring 127, interposed between the lower end part of the latching dog 125 and the shift key lever 53, urges the latching dog 125 counterclockwise toward the normal position in Figure 1, and thereby urges the shift key locking lever 54 clockwise to its normal position. The lower end of the dog 125 is formed with a nose 128 which

normally is disposed clear of, but which is adapted to engage under, a keeper 129 mounted on the frame.

In operation, when the shift key lock lever 54 is depressed, the latching dog 125 is rocked clockwise to bring its nose 128 against the rear face of the keeper 129, and the entire shift key structure E is depressed until the nose 128 passes below and then projects under the keeper 129. When the finger pressure on the shift lock key 54 is removed, the shift key structure E is held in its depressed position by engagement of the nose 128 with the keeper 129, as shown in Figure 3. In order to return the parts to lower case positions, the shift key lever 53 is depressed so as to move the nose 128 of the latching dog out of contact with the keeper 129. This will enable the spring 127 to rock the latching dog 125 counterclockwise so that, upon relieving the pressure on the shift key lever 53, the entire key structure E will be returned to its normal or lower case position by the spring 68.

Figures 6 to 9, inclusive, show a typewriter embodying a case shifting mechanism generally the same as the mechanism described with reference to Figures 1 to 5, inclusive, and also a repeat typing mechanism, only a part of which is shown in Figure 1. The case shifting mechanism included in the embodiment shown in Figures 6 to 9 is so similar to the mechanism described with reference to Figures 1 to 5 that no repeated detailed description of the mechanism shown in Figures 6 to 9, inclusive, is believed to be necessary. Some of the parts of the case shifting mechanism shown in Figures 6 to 9, inclusive, are identical to corresponding parts described with reference to Figures 1 to 5, inclusive, and are designated by the same reference characters. Other parts of the case shifting mechanism shown in Figures 6 to 9, inclusive, which differ from the mechanism shown in Figures 1 to 5, inclusive, mainly as to form will be referred to briefly.

Figure 6 shows a portion of a case shift actuator 130 which corresponds to the actuator 29 shown in Figure 1. The actuator 130 is pivoted at 131 to a combined pull link and shift locking bar or case shift actuator and retainer 132 which corresponds to the link 75 and the bar 86 in the form shown in Figures 1 to 5, inclusive. The bar 132 is formed in one piece and is not adjustable as to length except by mauling or bending. Such a unitary bar may be used with good results when manufactured to close tolerances. The rear end of the bar 132 is connected to the shift arm 8, preferably by a cushion lever device, not shown in Figure 6, but which may be of the kind shown in Figure 1. The front end of the bar 132 rides on top of the abutment 35 instead of having guide lugs corresponding to the lugs 104 in the construction shown in Figures 1 to 5, inclusive. The projection 133 on the front end of the bar 132 is rounded, and the cooperating locking pawl 134 has its tail 135 extending more forwardly than the tail 111 of the pawl 107 shown in Figures 1 to 5, inclusive. The holding dog 136 is pivoted as at 137 on a bracket 138 extending rearwardly from a fixed frame part instead of downwardly, as does the bracket 114 shown in Figures 1 and 3.

A further difference between the constructions shown in Figures 1 to 5, inclusive, and in Figures 6 to 9, inclusive, is that in the latter form the shift lock dog 24 is operated directly by key effort instead of by the shift actuator 130. As shown in Figures 6 and 7, the shift key structure

E is formed with a projection 139 connected to the dog 24 by a link 140 which is pivoted to the projection 139 as at 141, and is pivoted to the dog 24 as at 142.

The shift mechanism actuator 130 shown in Figure 6 is equipped with an interponent pawl and trigger and associated elements not shown, but which correspond to the interponent pawl 45, trigger 48, and associated elements shown in Figure 1. It will be apparent that the operation of the case shift mechanism, per se, under the control of the shift key structure E is essentially the same as the operation of the mechanism shown in Figures 1 to 5, inclusive.

Mechanism shown in Figures 6 to 9 for effecting repeated typing operations of the typing member 27 includes a single tooth interponent 143 and associated mechanism corresponding to the interponent 45 and associated mechanism shown in Figure 1. The interponent 143 is pivotally mounted as at 144 on an actuator 145 which, in turn, is pivoted as at 146 to a lever 147 mounted to rock on a fixed frame pivot 148 on a cross bar 149. The upper end of the lever 147 is pivoted at 150 to a wire link 151, the rear end of which is pivoted at 152 to the heel 153 of the typing member 27.

The interponent 143 is formed similarly to the interponent 45 so as to have a holding surface 154 and a re-setting cam surface 155. The interponent 143 is controlled by a trigger 156 pivotally mounted on the actuator 145 as at 157. When the trigger 156 is rocked clockwise so as to release the interponent 143, the latter will be driven by the snatch roll 28 so as to move the assembly constituted by the interponent 143, trigger 156, and actuator 145 forwardly, rock the lever 147 forwardly, pull the link 151 forwardly, and thus move the type bar 27 to printing position.

The actuator 145 and interponent 143 have relatively adjustable parts 158 and 159, respectively, for varying the driving effort transmitted to the type bar 27. In other respects the parts of the mechanism D shown in Figure 6 are generally similar to parts embodied in the construction shown in Figures 1 to 5, inclusive, so that no more detailed description of the mechanism D shown in Figure 6 is considered necessary.

As previously stated, the type bar 27 is provided with a lower case character 27^a and an upper case character 27^b which, in the form described, is an underlining character. In accordance with the invention, mechanism is provided for effecting a single type impression by the character 27^b or, alternatively, to effect automatically repeated impressions by the underlining character 27^b. In accordance with a further feature of the invention, the movement of the segment 4 to upper case position and the automatic repeated operation of the type bar 27 may be effected by depression of a single key or other manually manipulatable element, or alternatively typing member 27^b may be caused to perform a single typing operation by depressing another key when the segment 4 has been shifted to upper case position by depression of the shift key structure E.

The mechanism for effecting single operations of the type bar 27 includes a key lever 160 pivoted on a fixed part of the frame as at 108. An upward extension 161 on the rear end of the key lever 160 projects behind the depending arm 162 of a lever 163 pivoted at 61 on the frame cross bar 62. Pivoted at 164 on another arm 165 of the lever 163 is a limber dog or flipper 166 urged

clockwise by a spring 167 but limited in its clockwise movement by a stop ear 168 on the lever arm 165. The lower end of the flipper 166 is disposed above a contact ear 169 on the type bar actuator 145 previously referred to. A spring 170 is interposed between the key lever 160 and an arm 171 on the lever 163 for normally maintaining the parts in the positions shown in Figure 6.

In operation, when the single impression character key lever 160 is depressed the lever 163 is rocked clockwise, causing the flipper 166 to engage the actuator ear 169 and move the actuator 145 downwardly until its associated trigger 156 is rocked to pawl-releasing position by engagement with the lower abutment 38. The pawl or interponent 143, having been thus released, will move into engagement with the snatch roll 28 so as to be driven forwardly together with the actuator 145, thus rocking the lever 147 and actuating the type bar 27 through the link connection 151. When the interponent 143 has been cast off the snatch roll 28 the parts will return to their normal positions even though the key 160 be held depressed so that only a single actuation of the type bar 27 will take place. For a more detailed description of the sequence of operation of the parts for actuating the type bar 27, reference is made to the detailed description of the analogous operation of the interponent 45 and its associated parts shown in Figure 1.

It will be understood that the operation of the type bar 27 effected by depression of the key 160 is independent of operation of the case shifting mechanism and its associated controlling devices. Thus the type bar 27 can be caused to perform a single typing operation regardless of the position in which the type bar segment 4 is set. Moreover, the case shift mechanism may be operated by depressing the key structure E without operating the type bar 27.

It is, however, a further feature of the invention that the case shifting mechanism and the mechanism for operating the type bar 27 may be articulated so as to be operated under the control of a single manually manipulatable element first to shift the segment 4 to upper case position, and then automatically to effect repeated operations of the type bar 27 as long as the manipulatable element is held in manipulated position. Such an arrangement has particular advantages when the type bar 27 has an upper case under-scoring character as shown at 27^b in Figure 1.

In the form shown, a combined case shift and repeat typing operation key lever 172 has its front arm 173 extending through a slot 174 in the front wall of the typewriter mask or cover. The lever 172 is pivoted as at 175 and has a rearwardly extending arm 176 pivoted at 177 to the upper end of a link 178, the lower end of which is pivoted at 179 to the rear end of a lever 180 pivoted at 108. A link 181 is pivoted at 182 to the lever 180 and is pivoted at 183 to an arm 184 fixed to a rock shaft 185. A link member 186 is pivoted at 187 to another arm 184^a fixed to the shaft 185, and extends upwardly with its upper end part being connected to the type bar actuator 145 by a pin and slot one-way-acting motion transmitting connection 188. The arrangement is such that when the link member 186 is moved downwardly the actuator 145 is lowered so as to effect releasing of the pawl 143 by the trigger 156 and consequent driving engagement of the pawl with the snatch roll 28. However, when the link

186 is not moved, the actuator 145 may still be moved downwardly by the key 160, lever 163 and flipper 166 in the manner previously described.

Normally, the lever 172, the link 186 and the intervening connections are in the positions shown in full lines in Figure 6 with a stop part 189 engaging a fixed frame part 190 so as to determine the unactuated positions of the parts. In order to effect repeated operation of the type bar 27, the key 172 is depressed to the dotted line position shown in Figure 6 which is determined by engagement of a stop part 191 with the fixed frame part 190. Depression of the key 172 lifts the link 178 so as to rock the lever 180 counterclockwise, lift the link 181, rock the movable part constituted by the arms 184 and 184^a, and the shaft 185 clockwise, and move the link 186 downwardly to lower the actuator 145. Lowering of the actuator 145 causes the trigger 156 to engage the lower abutment 38 and be rocked to interponent-releasing position, whereupon the interponent 143 engages the snatch roll 28 and is driven forwardly together with the actuator 145 to operate the type bar 27. During the forward movement of the actuator 145, the link 186 will rock clockwise about its pivot 187. When the interponent 143 is cast off the snatch roll 28 the actuator 145 will return or move rearwardly while the link 186 rocks clockwise and continues to hold the actuator down so as to prevent engagement of the trigger 156 with the upper abutment 35. Consequently, the trigger 156 will not be rocked to re-set the pawl 143, and the latter will re-engage the snatch roll 28, and will again be driven forwardly to effect another operation of the type bar 27. Repeated cycles or operations of the actuator and type bar will take place in this manner as long as the key 172 is held depressed with consequent holding of the link 186 in its lowered position.

In order that the machine may be conditioned for typing the upper case character 27^b when repeated operation of the type bar 27 is effected by depressing the key 172, a one-way-acting connection is provided for depressing the shift key structure E when the key lever 172 is actuated. In the form shown, the lever 180 has a rounded front end 192 normally disposed above a contact part 193 on the case shift lever 53. The contact part 193 is formed with high points 194 and 195 and an intervening recessed part 196 which is substantially concentric with the pivot 108 when the parts are in their normal positions.

In operation, when the lever 180 is rocked counterclockwise by manipulation of the key lever 172, the rounded end or bearing part 192 engages the high point 194 on the contact or bearing part 193 and transmits force from the repeat key 172 to the shift key so as to rock the shift key lever 53 downwardly concomitantly with depression of the key 172 to thus effect shifting of the segment 4 to its upper case position in the manner previously described. When the key lever 172 and associated parts are in their completely actuated positions, the rounded end 192 of the lever 180 will be in contact with the recessed part 196 of the contact member 193 so as to hold the shift key lever 53 depressed with the application of minimum finger pressure on the key lever 172. The parts are so proportioned and related and the timing of the mechanism is such that when the key lever 172 is depressed the shift mechanism will move the segment 4 to its upper case

position before the type bar 27 arrives in printing position on its first stroke.

The case shift mechanism shown in Figures 1 to 5, inclusive, is intended for use in connection with the repeat type bar operating mechanism described with reference to Figure 6. However, to avoid undue complication of the drawings, Figure 1 shows only a part of the repeat type bar operating mechanism as including the lower end of the link 181, the shaft 185, the rock arms 184 and 184^a, all of which have been described with reference to Figure 6.

Figures 10 to 12, inclusive, illustrate a modified construction which, like the forms previously described, includes a single manipulatable member for effecting case shifting operation and automatically repeated type bar operation. The mechanism for articulating the case shift mechanism and repeat typing mechanism differs somewhat from the articulating mechanism previously described and will be explained in some detail. However, the shift mechanism shown in Figures 10 to 12, inclusive, and the repeat typing mechanism shown in these figures, considered alone, are so generally similar to the shift mechanism and repeat typing mechanism described above that a brief description of the shift mechanisms and the repeat typing mechanisms will suffice. Generally stated, parts of the case shifting mechanism and the repeat typing mechanism shown in Figures 10 to 12, inclusive, are designated by the same reference numerals as those designating corresponding parts previously described, the numerals designating these parts in Figures 10 to 12, inclusive, however, being primed. Thus, the snatch roll 28' shown in Figure 10 corresponds to the snatch roll 28 shown in Figures 1, 3 and 6, the shift actuator 130' shown in Figures 10 to 12, inclusive, corresponds to the shift actuator 130 shown in Figure 6, the repeat typing actuator 145' shown in Figures 10 to 12, inclusive, corresponds to the actuator 145 shown in Figure 6, and so on. It may be observed that some of the parts shown in Figures 10 to 12 differ in specific construction from the corresponding parts shown in the figures described previously, but not in such manner as to affect the basic combination or mode of operation of the parts. For example, the interponent pawls 143' and 45', shown in Figures 10 to 12, differ from their counterparts 143 and 45 by having ears 197 and 198 engageable with depending parts 199 and 200 of their associated actuators. The ears 197 and 198 project horizontally and may be bent or adjusted to vary the extent to which the associated interponents or pawls move into the tooth interspaces in the snatch roll, thus serving the same purpose as the relatively adjustable parts 72-73 in Figure 1, and 158-159 in Figure 6. Other minor differences in construction observable in Figures 10 to 12, inclusive, need not be described.

The means for articulating the caseshifting and repeat typing mechanisms shown in Figures 10 to 12, inclusive, comprises a lever 201 extending longitudinally of and in front of the machine and being pivoted as at 202 on the machine frame. An arm 203 of the lever 201 is equipped with a key button 204, the other arm 205 of the lever 201 being pivoted as at 206 to the upper end of a link 207, the lower end of which is pivoted as at 208 to a lever 209 mounted to rock on a pivot 52'. The rear end of the lever 209 is pivoted at 210 to the lower end of a link 211, the top of which has a pin and slot one-way-acting con-

nection at 212 with the type bar actuator 145'.

In operation, when the key 204 is depressed the lever 201 is rocked to lift the link 207, rock the lever 209, and move the link 211 downwardly so as to effect engagement of the interponent pawl 143' with the snatch roll 28', resulting in operation of the actuator 145' and type bar 27'. Having in mind the previous description, it will be understood that the type bar 27' will be operated repeatedly as long as the key 204 is held depressed.

In order that the key 204 may also effect operation of the shifting mechanism, a thrust link 213 is pivoted at 214 to the arm 203 of the key lever 201, and has its lower end formed with a fork 215 which receives the rod 55' joining the shift key levers 53'. The fork 215 and rod 55' provide a one-way-acting connection for transmitting depressing movement of the key 204 to the shift key E'. When the lever 201 is rocked by depressing the key 204, the link 213 is moved downwardly so as to push the rod 55' and depress the shift key structure E'. Engagement of the shift mechanism interponent 45' with the snatch roll 28' and consequent operation of the shift mechanism will then ensue in the manner previously described.

Although modifications of structures embodying the invention have been illustrated, they have, as common advantages, a lightness of the finger pressure required for effecting case shifting and maintaining the shiftable element in shifted position, and the flexibility of operations permitted by the novel means articulating the case shifting mechanism and the repeat typing mechanism. Thus, in machines embodying the invention, the shiftable element may be operated alone, or together with the repeat typing mechanism to effect continuous typing by an upper case character, or the same upper case character may be typed only once.

The constructions described with reference to the accompanying drawings embody the invention in preferred forms, but it is intended that they be considered as illustrative rather than definitive of the invention. The invention is defined in the claims.

I claim:

1. In a power operated typewriting or like machine, a case shift element; a power driven member; a case shift actuator; means connecting said actuator to said element; a shift key; means operable by said key for effecting driving of said actuator and said element to shifted positions by said member; a retaining device movable from a normally inactive position to a position of engagement with said actuator in which position said device is adapted to be held for retaining said actuator in its shifted position; a holding part movable from a normally inactive position towards a position of engagement with said retaining device in which position said part holds said device in retaining engagement with said actuator; and means associated with said key and normally maintaining said holding part out of operative engagement with said retaining device but being movable by said key to release said holding part and enable it to move into holding engagement with said retaining device when said key is in actuated position.

2. In a power operated typewriting or like machine, a case shift element; a power driven member; a case shift actuator; means connecting said actuator to said element; a shift key; means op-

erable by said key for effecting driving of said actuator and said element to shifted positions by said member; a retaining device spring-urged to move from a normally inactive position to a position of engagement with said actuator in which position said device is adapted to be held for retaining said actuator in its shifted position; a holding part spring-urged to move from a normally inactive position towards a position of engagement with said retaining device in which position said part holds said device in retaining engagement with said actuator; and means associated with said key and including a blocking part normally maintaining said holding part out of operative engagement with said retaining device but being movable by said key to release said holding part and enable it to be moved by spring urge into holding engagement with said retaining device when said key is in actuated position.

3. In a power operated typewriting or like machine, a case shift element; a power driven member; a case shift actuator; means connecting said actuator to said element; a shift key; means operable by said key for effecting driving of said actuator and said element to shifted positions by said member; a retaining device movable from a normally inactive position to a position of engagement with said actuator in which position said device is adapted to be held for retaining said actuator in its shifted position; a holding part movable from a normally inactive position towards a position of engagement with said retaining device in which position said part holds said device in retaining engagement with said actuator; a spring connected respectively to said retaining device and said holding part and urging said retaining device towards its position for retaining said actuator in its shifted position, and urging said holding part towards its position of engagement with said retaining device; and means associated with said key and normally maintaining said holding part out of operative engagement with said retaining device but being movable by said key to release said holding part and enable it to be moved by said spring into holding engagement with said retaining device when said key is in actuated position.

4. In a power operated typewriting or like machine, a case shift element; a power driven member; a case shift actuator; means connecting said actuator to said element; a shift key; means operable by said key for effecting driving of said actuator and said element to shifted positions by said member; a projection on said actuator; a pivoted retaining pawl having a surface slidably engaged by said projection during operation of said actuator and a nose adapted to move into locking engagement with said projection when said actuator has moved to its completely shifted position wherein said projection has moved clear of said pawl surface; a pivoted holding dog normally operatively disengaged from said pawl; means biasing said pawl into engagement with said projection and biasing said dog into operative engagement with said pawl when the pawl nose is in locking engagement with said projection for holding said pawl nose in locking engagement with said projection; and a blocking part normally maintaining said dog operatively disengaged from said pawl but being operable in response to actuation of said key for enabling said biasing means to move said dog into operative engagement with said pawl.

5. In a power operated typewriting or like machine, a case shift element; a power driven mem-

ber; a case shift actuator; means connecting said actuator to said element; a shift key; means operable by depression of said key for effecting driving of said actuator and said element to shifted positions by said member; means controlled by said key upon raising thereof for effecting returning of said actuator and said element to their non-shifted positions; a retaining device movable from a normally inactive position to a position of engagement with said actuator in which position said device is adapted to be held for retaining said actuator in its shifted position, the mutually engageable parts of said retaining device and said actuator comprising cam means operable by said actuator returning means when said device is not held for camming said device out of retaining engagement with said actuator; a holding part movable from a normally inactive position towards a position of engagement with said retaining device in which position said part holds said device in retaining engagement with said actuator; and means associated with said key and normally maintaining said holding part out of operative engagement with said retaining device but being movable by said key to release said holding part and enable it to move into holding engagement with said retaining device when said key is in actuated position, and being movable by raising of said key for moving said holding part out of operative engagement with said retaining device.

6. In a power operated typewriting or like machine, a case shift element; a power driven member; a case shift actuator; means mounting said actuator for oscillation, said actuator being formed with a first surface extending generally in the direction of oscillation and a second surface inclined with respect thereto; means connecting said actuator to said element; a shift key; means operable by said key for effecting driving of said actuator and said element to shifted positions by said member; means for returning said actuator and said element to their normal non-shifted positions; a pivoted pawl having a first surface normally engaging said first actuator surface and extending generally in the direction of oscillatory movement thereof and having also a retaining surface inclined with respect to said direction of oscillator movement; means so biasing said pawl as normally to hold its said first surface in engagement with said actuator first surface and being adapted to rock said pawl when said actuator first surface moves beyond said pawl first surface consequent to shifting of said actuator so as to bring said pawl into actuator-retaining position with said pawl and actuator inclined surfaces in engagement with each other, the pawl-biasing means however being in itself insufficiently strong to resist displacement of said inclined pawl surface from engagement with said actuator inclined surface by the camming action of said surfaces upon each other under the urge of said actuator returning means; a holding dog normally operatively disengaged from said pawl; and means responsive to movement of said key to shift-effecting position for moving said dog into engagement with said pawl for holding said pawl in said actuator-retaining position as long as said key is held depressed.

7. In a power operated typewriting or like machine, a case shift element; a power driven member; a case shift actuator; means connecting said actuator to said element; a shift key; means operable by said key for effecting driving of said actuator and said element to shifted positions by

said member; means for returning said actuator and said element from shifted to non-shifted positions; a retaining device movable from a normally inactive position into a position in which it tends to prevent return movement of the actuator but insufficiently, in itself, to prevent such movement; a normally ineffective holding part; and means responsive to operation of said key and resultant shifting of said actuator and said element for rendering said holding part effective to supplement said tendency of said retaining device whereby said actuator and said element are held in shifted positions jointly by said retaining device and said holding part as long as said key is held in operated position.

8. In a power operated typewriting or like machine, a case shift element; a power driven member; a case shift actuator; a shift lock for normally holding said element in normal, non-shifted position; means connecting said lock to said actuator to be operated thereby to non-locking position to enable said element to be shifted; means connecting said actuator to said element; a shift key; means operable by said key for effecting driving of said actuator and said element to shifted positions by said member; a retaining device movable from a normally inactive position to a position of engagement with said actuator in which position said device is adapted to be held for retaining said actuator in its shifted position; a holding part movable from a normally inactive position towards a position of engagement with said retaining device in which position said part holds said device in retaining engagement with said actuator; and means associated with said key and normally maintaining said holding part out of operative engagement with said retaining device but being movable by said key to release said holding part and enable it to move into holding engagement with said retaining device when said key is in actuated position.

9. In a power operated typewriting or like machine, a case shift element; a power driven member; a case shift actuator; a shift lock for normally holding said element in normal, non-shifted position; means connecting said actuator to said element; a shift key; means operable by said key for moving said lock to non-locking position to enable said element to be shifted and for effecting driving of said actuator and said element to shifted positions by said member; a retaining device movable from a normally inactive position to a position of engagement with said actuator in which position said device is adapted to be held for retaining said actuator in its shifted position; a holding part movable from a normally inactive position towards a position of engagement with said retaining device in which position said part holds said device in retaining engagement with said actuator; and means associated with said key and normally maintaining said holding part out of operative engagement with said retaining device but being movable by said key to release said holding part and enable it to move into holding engagement with said retaining device when said key is in actuated position.

10. In a power operated typewriting or like machine, a case shift element; a power driven member; a case shift actuator; cushioned drive-transmitting connections between said actuator and said element comprising a first lever connected to said element, a second lever pivotally mounted with respect to said first lever, a force-transmitting spring connecting said levers, and means connecting said second lever to said ac-

tuator; a shift key; means operable by said key for effecting driving of said actuator and said element to shifted positions; a retaining device movable from a normally inactive position to a position of engagement with said actuator in which position said device is adapted to be held for retaining said actuator in its shifted position; a holding part movable from a normally inactive position towards a position of engagement with said retaining device in which position said part holds said device in retaining engagement with said actuator; and means associated with said key and normally maintaining said holding part out of operative engagement with said retaining device but being movable by said key to release said holding part and enable it to move into holding engagement with said retaining device when said key is in actuated position.

11. In a power operated typewriting or like machine, a case shift element; a power driven member; a case shift actuator; cushioned drive-transmitting connections between said actuator and said element comprising a first lever connected to said element, a second lever pivotally mounted with respect to said first lever, a force-transmitting spring connecting said levers, and means connecting said second lever to said actuator; a shift key; means operable by said key for effecting driving of said actuator and said element to shifted positions; means for returning said actuator and said element from shifted to non-shifted positions; a retaining device movable from a normally inactive position into a position in which it tends to prevent return movement of the actuator but insufficiently, in itself, to prevent such movement; a normally ineffective holding part; and means responsive to operation of said key and resultant shifting of said actuator and said element for rendering said holding part effective to supplement said tendency of said retaining device whereby said actuator and said element are held in shifted positions jointly by said retaining device and said holding part as long as said key is held in operated position.

12. In a power operated typewriting or like machine, a case shift element; a power driven member; a case shift actuator; means connecting said actuator to said case shift element; an interponent mounted on said actuator for movements into and out of operative engagement with said driven member and being biased into engagement therewith; a trigger normally maintaining said interponent disengaged from said driven member; a shift key; means responsive to depression of said key for actuating said trigger to release said interponent and enable it to move into engagement with said driving member, whereby said actuator will be driven by said driven member so as to operate said case shift element; trigger re-setting means effective upon return movement of said shift key when said driven member is stationary for moving said trigger reversely to its releasing movement and thereby disengaging said interponent from said driving member; means for returning said actuator and said element from shifted to non-shifted positions; a retaining device movable from a normally inactive position into a position in which it tends to prevent return movement of the actuator but insufficiently, in itself, to prevent such movement; a normally ineffective holding part; and means responsive to operation of said key and resultant shifting of said actuator and said element for rendering said holding part effective to supplement said tendency of said retaining device

whereby said actuator and said element are held in shifted positions jointly by said retaining device and said holding part as long as said key is held in operated position.

13. In power operating mechanism for a typewriting or like machine, a typing member; a power-driven member; an actuator; means connecting said actuator to said typing member; an interponent mounted on said actuator for movements into and out of operative engagement with said driven member and being biased to move from a normal position in which it is disengaged from said actuator into operative engagement therewith; a trigger mounted on said actuator and normally maintaining said interponent disengaged from said driven member, said actuator, interponent, and trigger constituting an assembly of conjointly movable parts; a typing control mechanism including an element manipulatable for actuating said trigger to release said interponent and enable it to move into engagement with said driven member whereby said actuator will be driven by said driven member to operate said typing member during the course of which operation said interponent is thrown out of engagement with said driven member; and means for then returning said actuator towards its normal non-actuated position, said typing control mechanism including means comprising a member operable by said manipulatable element and being connected to and having a part movable with said assembly during operating movements of said assembly for maintaining said trigger in actuated, interponent-releasing position when said manipulatable element is held in manipulated position, whereby, during returning of said actuator towards its normal non-actuated position, said interponent will re-engage said driven member to be repeatedly driven thereby for effecting repeated driving of said actuator and repeated typing operations of said typing member.

14. In power operating mechanism for a typewriting or like machine, a typing member; a power-driven member; an actuator; means connecting said actuator to said typing member; an interponent mounted on said actuator for movements into and out of operative engagement with said driven member and being biased to move from a normal position in which it is disengaged from said actuator into operative engagement therewith; a trigger mounted on said actuator and normally maintaining said interponent disengaged from said driven member, said actuator, interponent, and trigger constituting an assembly of conjointly movable parts; a typing control mechanism including an element manipulatable for actuating said trigger to release said interponent and enable it to move into engagement with said driven member whereby said actuator will be driven by said driven member to operate said typing member during the course of which operation said interponent is thrown out of engagement with said driven member; means for then returning said actuator towards its normal non-actuated position, said typing control mechanism including means comprising a member operable by said manipulatable element and being connected to and having a part movable with said assembly during operating movements of said assembly for maintaining said trigger in actuated, interponent-releasing position, when said manipulatable element is held in manipulated position, whereby, during returning of said actuator towards its normal non-actuated position,

ated position, said interponent will re-engage said driven member to be repeatedly driven thereby for effecting repeated driving of said actuator and repeated typing operations of said typing member; and trigger-resetting means responsive to returning of said manipulatable element to normal, non-manipulated position for moving said trigger reversely to its releasing movement and thereby returning said interponent to its normal position on said actuator.

15. In power operating mechanism for a type-writing or like machine, a typing member; a power-driven member; an actuator; means connecting said actuator to said typing member; an interponent mounted on said actuator for movements into and out of operative engagement with said driven member and being biased to move from a normal position in which it is disengaged from said actuator into operative engagement therewith; a trigger pivotally mounted on said actuator and normally maintaining said interponent disengaged from said driven member, said actuator, interponent, and trigger constituting an assembly of conjointly movable parts; a re-setting cam face on said interponent; a typing control mechanism including an element manipulatable for actuating said trigger in one direction about its pivot to release said interponent and enable it to move into engagement with said driven member whereby said actuator will be driven by said driven member to operate said typing member during the course of which operation said interponent is thrown out of engagement with said driven member; means for then returning said actuator towards its normal non-actuated position, said typing control mechanism including means comprising a member operable by said manipulatable element and being connected to and having a part movable with said assembly during operating movements of said assembly for maintaining said trigger in actuated, interponent-releasing position when said manipulatable member is held in manipulated position, whereby, during returning of said actuator towards its normal non-actuated position, said interponent will re-engage said driven member to be repeatedly driven thereby for effecting repeated driving of said actuator and repeated typing operations of said typing member; and means responsive to returning of said manipulatable element to normal, non-manipulated position for rocking said trigger reversely about its pivot to move a part of said trigger against said re-setting cam face and thus move said interponent from engagement with said driven member.

16. In power operating mechanism for a type-writing or like machine, a typing member; a power-driven member; an actuator; means connecting said actuator to said typing member; an interponent mounted on said actuator for movements into and out of operative engagement with said driven member and being biased to move from a normal position in which it is disengaged from said actuator into operative engagement therewith; a trigger normally maintaining said interponent disengaged from said driven member; a typing control mechanism including a link pivotally connected at one of its ends to said actuator, a movable part to which the other end of said link is pivotally connected, and a manipulatable element for moving said movable part, said link, and said actuator to actuate said trigger to release said interponent and enable it to move into engagement with said driven member

whereby said actuator will be driven by said driven member to operate said typing member during the course of which operation said interponent is thrown out of engagement with said driven member; and means for then returning said actuator towards its normal non-actuated position, said link, when held in the position to which it is moved by said manipulatable element and said part movable thereby, holding said actuator and interponent in position for reengagement of said interponent with said driven member when said actuator is being returned toward its non-actuated position, thereby effecting repeated driving of said actuator and said typing member by said driven member while said manipulatable member is held in manipulated position.

17. In power operating mechanism for a type-writing or like machine, a typing member; a rotatable driven member; a movably mounted actuator; means operatively connecting said actuator to said typing member; an interponent mounted movably on said actuator; a spring urging said interponent to move into drive-transmitting engagement with said driven member; a trigger mounted movably on said actuator and normally occupying a position in which it maintains said interponent out of drive-transmitting engagement with said driven member, said actuator, interponent, and trigger constituting an assembly of conjointly movable parts; an abutment; key-controlled means for moving said actuator to move said interponent towards but not into engagement with said driven member and simultaneously to move said trigger into engagement with said abutment to thereby actuate said trigger to release said interponent and enable the latter to be moved by said spring into drive-transmitting engagement with said driven member, whereby said actuator will be driven through said interponent until the latter is thrown out of engagement with said driven member; means for urging said actuator to return to normal position upon such disengagement of said interponent from said driven member; a second abutment engageable by said trigger when said actuator is so return-moved for returning said trigger to its initial position on said actuator; and means associated with said trigger and said interponent for returning said interponent to its normal position when said trigger is returned to its initial position, said key controlled means including mechanism comprising a member connected to and having a part movable with said assembly during operating movements of said assembly for preventing engagement of said trigger with said second abutment as long as said key-controlled means is in operated position.

18. In power operating mechanism for a type-writing or like machine, a typing member; a rotatable driven member; a movably mounted actuator; means operatively connecting said actuator to said typing member; an interponent mounted movably on said actuator; a spring urging said interponent to move into drive-transmitting engagement with said driven member; a trigger mounted movably on said actuator and normally occupying a position in which it maintains said interponent out of drive-transmitting engagement with said driven member, said actuator, interponent, and trigger constituting an assembly of conjointly movable parts; an abutment; key-controlled means for moving said actuator to move said interponent towards but not into engagement with said driven member and simultaneously to move said trigger into engagement

with said abutment to thereby actuate said trigger to release said interponent and enable the latter to be moved by said spring into drive-transmitting engagement with said driven member, whereby said actuator will be driven through said interponent until the latter is thrown out of engagement with said driven member; means for urging said actuator to move reversely to the direction in which it was moved by said key-controlled means and reversely to the direction in which it was driven by said driven member; a second abutment engageable by said trigger when said actuator is moved reversely to the direction in which it was moved by said key-controlled means for returning said trigger to its initial position on said interponent; and means associated with said trigger and said key-controlled means including mechanism comprising a member connected to and having a part movable with said assembly during operating movements of said assembly and being effective as long as said key-controlled means is in actuated condition for preventing said actuator from moving reversely to the direction in which it was moved by said key-controlled means while permitting said actuator repeatedly to move alternately in the direction in which it is driven by said driven member and reversely thereto, whereby to effect repeated engagement and disengagement of said interponent and said driven member with consequent repeated operation of said typing member.

19. In power operating mechanism for a typewriting or like machine, a typing member; a rotatable driven member; a movably mounted actuator; means operatively connecting said actuator to said typing member; an interponent mounted movably on said actuator; a spring urging said interponent to move into drive-transmitting engagement with said driven member; a trigger mounted movably on said actuator and normally occupying a position in which it maintains said interponent out of drive-transmitting engagement with said driven member; an abutment; key-controlled means for moving said actuator to move said interponent towards but not into engagement with said driven member and simultaneously to move said trigger into engagement with said abutment to thereby actuate said trigger to release said interponent and enable the latter to be moved by said spring into drive-transmitting engagement with said driven member, whereby said actuator will be driven through said interponent until the latter is thrown out of engagement with said driven member; means for urging said actuator to move reversely to the direction in which it was moved by said key-controlled means and reversely to the direction in which it was driven by said driven member; a second abutment engageable by said trigger when said actuator is moved reversely to the direction in which it was moved by said key-controlled means for returning said trigger to its initial position on said interponent; and means associated with said trigger and said interponent for returning said interponent to its normal position on said actuator when said trigger is returned to its initial position on said actuator, said key-controlled means including a lever, a link pivotally connected at its opposite ends respectively to said actuator and to said lever, and key-operated means for rocking said lever and thus moving said link and said actuator, said link being effective as long as said key-operated means is in actuated condition for preventing said actuator from moving reversely to the direction in which it was moved by said key-con-

trolled means while permitting said actuator repeatedly to move alternately in the direction in which it is driven by said driven member and reversely thereto, whereby to effect repeated engagement and disengagement of said interponent and said driven member with consequent repeated operation of said typing member.

20. In a power operating mechanism for a typewriting or like machine, a typing member; a rotatable driven member; a movably mounted actuator extending transversely to the axis of rotation of said driven member and having a part thereon normally disengaged from said driven member but being engageable therewith upon being moved relatively toward said driven member for effecting driving of said actuator by said driven member; means operatively connecting said actuator to said typing member; a key-operated lever; and a link extending substantially transversely to the direction of driving of said actuator by said driven member and being pivotally connected at its opposite ends respectively to said lever and to said actuator for moving said actuator relatively towards said driven member to effect engagement of said part on said actuator with said driven member and for holding said actuator against reverse movement relatively away from said driven member while permitting said actuator to be driven by said driven member repeatedly as long as said lever is in key-operated position.

21. In a power operating mechanism for a typewriting or like machine, a typing member; a rotatable driven member; a movably mounted actuator extending transversely to the axis of rotation of said driven member and having a part thereon normally disengaged from said driven member but being engageable therewith upon being moved relatively toward said driven member for effecting driving of said actuator by said driven member; means operatively connecting said actuator to said typing member; a single impression character key; key-actuated means operable by depression of said key for moving said actuator towards said driven member to effect engagement of said part on said actuator with said driven member whereby said actuator is driven by said driven member to effect a single typing stroke of said typing member, said key-actuated means including a part mounted to yield if said single impression character key is held depressed following driving of said actuator by said driven member so as not to interfere with returning of said actuator to its normal position after being driven by said driven member; a repeat key; means including a pivoted link operable by said repeat key; a one-way-acting connection between said link and said actuator for transmitting motion from said link to said actuator for moving said actuator toward said driven member to bring said part on said actuator into engagement with said driven member and for holding said actuator against reverse movement away from said driven member while permitting said actuator to be driven repeatedly by said driven member as long as said repeat key is held in operated position, said single impression character key and said repeat key being operable optionally for effecting single or repeated operation of said actuator, said one-way-acting connection enabling said actuator to be moved toward said driven member without being restrained by said link when said single impression character key is operated.

22. In a power operating mechanism for a typewriting or like machine, a typing member; a

rotatable driven member; a movably mounted actuator extending transversely to the axis of rotation of said driven member and having a part thereon normally disengaged from said driven member but being engageable therewith upon being moved relatively toward said driven member for effecting driving of said actuator by said driven member; means operatively connecting said actuator to said typing member; a single impression character key; key-actuated means operable by depression of said key for moving said actuator towards said driven member to effect engagement of said part on said actuator with said driven member whereby said actuator is driven by said driven member to effect a single typing stroke of said typing member, said key-actuated means including a part mounted to yield if said single impression character key is held depressed following driving of said actuator by said driven member so as not to interfere with returning of said actuator to its normal position after being driven by said driven member; a repeat key; means including a pivoted link operable by said repeat key; a pin-and-slot connection between said link and said actuator for transmitting motion from said link to said actuator for moving said actuator toward said driven member to bring said part on said actuator into engagement with said driven member and for holding said actuator against reverse movement away from said driven member while permitting said actuator to be driven repeatedly by said driven member as long as said repeat key is held in operated position, said single impression character key and said repeat key being operable optionally for effecting single or repeated operation of said actuator, the slot of said pin-and-slot connection extending in the direction in which said actuator is moved for bringing said part on said actuator into engagement with said driven member, whereby when said single character impression key is depressed said actuator may be moved with the pin of said pin-and-slot connection moving idly relatively in the slot thereof, whereby said pin-and-slot connection imposes no restraint on movement of said actuator by depression of said single character impression key.

23. In a power operating mechanism for a typewriting or like machine, a typing member; a rotatable driven member; a movably mounted actuator extending transversely to and above the axis of rotation of said driven member and having a part thereon normally disengaged from said driven member but being engageable therewith upon being moved downwardly toward said driven member for effecting driving of said actuator horizontally by said driven member; means operatively connecting said actuator to said typing member; a key-operated lever mounted above said actuator; a dog pivotally mounted on said lever and being engageable with said actuator for moving the latter downwardly and being yieldable horizontally so as not to interfere with horizontal movement of said actuator when said key-operated lever is held in operated position; a repeat key; a second lever mounted below said actuator and being operable by said repeat key; a vertically extending link; a pivotal connection between the lower end of said link and said second lever; and a pin-and-slot connection between the upper end of said link and said actuator.

24. In a power operated typewriter or like machine, a case shift element; a typing member having a type character thereon effective for typing only when said element is in shifted posi-

tion; a power driven member; a first actuator operatively connected to said case shift element and normally being disconnected from said power driven member but being connectable therewith for being driven thereby to move said element to shifted position; means including a manually manipulatable shift key operable for effecting connection of said first actuator to said driven member; means effective when said shift key is in operated position for holding said element in shifted position; a second actuator operatively connected to said typing member and normally being disconnected from said power driven member but being connectable therewith for being driven thereby to operate said typing member; a manually manipulatable repeat key; means responsive to operation of said repeat key and retaining of said repeat key in operated position for effecting repeated connection of said second actuator with said driven member with consequent repeated power operation of said second actuator by said driven member; and means on said repeat key for operating said shift key when said repeat key is operated.

25. In a power operated typewriter or like machine, a case shift element; a typing member having a type character thereon effective for typing only when said element is in shifted position; a power driven member; a first actuator operatively connected to said case shift element; a first interponent mounted on said first actuator for movements into and out of operative engagement with said power driven member and being biased to move into engagement therewith; a first trigger normally maintaining said first interponent disengaged from said power driven member; a second actuator operatively connected to said typing member; a second interponent mounted on said second actuator for movements into and out of operative engagement with said power driven member and being biased to move into engagement therewith; a second trigger normally maintaining said second interponent disengaged from said power driven member; a key; means responsive to depression of said key for actuating both said first trigger and said second trigger to release the respectively associated first and second interponents and enable them to move into engagement with said power driven member to thereby effect power driving of said first and second actuators by said driven member to shift said element and operate said typing member; means effective as long as said key is held depressed for retaining said case shift element in shifted position; and means effective when said key is held depressed for preventing returning of said second trigger and said second interponent to their normal positions on said second actuator, whereby said second interponent will remain positioned on said second actuator for repeatedly engaging and being driven by said power driven member as long as said key is held depressed.

26. In a power operated typewriter or like machine, a case shift element; a typing member having a type character thereon effective for typing only when said element is in shifted position; a power driven member; a first actuator operatively connected to said case shift element and normally being disconnected from said power driven member but being connectable therewith for being driven thereby to move said element to shifted position; a second actuator operatively connected to said typing member and normally being disconnected from said power driven member but being connectable therewith for being

driven thereby to operate said typing member; a repeat key; means responsive to depression of said repeat key for effecting connection of said first and second actuators with said power driven member whereby said actuators are operated by said power driven member respectively to shift said case shift element and to operate said typing member; means rendered effective when said first actuator has been operated and being maintained effective as long as said repeat key is held depressed for retaining said case shift element in operated position; and means effective as long as said repeat key is held depressed for causing repeated operation of said second actuator by said power driven member.

27. In a power operated typewriter or like machine, a case shift element; a typing member having a type character thereon effective for typing only when said element is in shifted position; a power driven member; a first actuator operatively connected to said case shift element and normally being disconnected from said power driven member but being connectable therewith for being driven thereby to move said element to shifted position; a second actuator operatively connected to said typing member and normally being disconnected from said power driven member but being connectable therewith for being driven thereby to operate said typing member; a manually operable shift key; means responsive to depression of said shift key for effecting connection of said first actuator with said power driven member whereby said first actuator will be power operated to shift said shift element; a manually operable second key; means responsive to depression of said second key for effecting connection of said second actuator with said power driven member whereby said second actuator will be power operated to operate said typing member; and a one-way-acting connection for transmitting force from said second key to said shift key for thereby depressing said shift key concomitantly with depression of said second key when the latter is depressed manually, said one-way-acting connection being incapable of transmitting force from said shift key to said second key.

28. In a power operated typewriter or like machine, a case shift element; a typing member having a type character thereon effective for typing only when said element is in shifted position; a power driven member; a first actuator operatively connected to said case shift element and normally being disconnected from said power driven member but being connectable therewith for being driven thereby to move said element to shifted position; a second actuator operatively connected to said typing member and normally being disconnected from said power driven member but being connectable therewith for being driven thereby to operate said typing member; a shift key; means responsive to depression of said shift key for effecting connection of said first actuator with said power driven member whereby said first actuator will be power operated to shift said shift element; a second key; means responsive to depression of said second key for effecting connection of said second actuator with said power driven member whereby said second actuator will be power operated to operate said typing member; a first bearing part on said shift key; a pivoted lever having a second bearing part normally operatively disconnected from said first bearing part; and means connecting said second key to said lever and operable upon depression of said second key for rocking said

lever to cause said second bearing part to bear on said first bearing part and thereby depress said shift key.

29. In a power operated typewriter or like machine, a case shift element; a typing member having a type character thereon effective for typing only when said element is in shifted position; a power driven member; a first actuator operatively connected to said case shift element and normally being disconnected from said power driven member but being connectable therewith for being driven thereby to move said element to shifted position; a second actuator operatively connected to said typing member and normally being disconnected from said power driven member but being connectable therewith for being driven thereby to operate said typing member; a shift key; means responsive to depression of said shift key for effecting connection of said first actuator with said power driven member whereby said first actuator will be power operated to shift said shift element; a second key; means responsive to depression of said second key for effecting connection of said second actuator with said power driven member whereby said second actuator will be power operated to operate said typing member; an endwise movable thrust link connected at one of its ends to said second key and at its other end being formed with a fork; and a part fast with said shift key and being received by said fork so as to form therewith a one-way-acting connection for transmitting depressing movement of said second key to said shift key but not from said shift key to said second key.

30. In a power operated typewriter or like machine, a case shift element; a typing member having a type character thereon effective for typing only when said element is in shifted position; a power driven member; a first actuator operatively connected to said case shift element and normally being disconnected from said power driven member but being connectable therewith for being driven thereby to move said element to shifted position; a second actuator operatively connected to said typing member and normally being disconnected from said power driven member but being connectable therewith for being driven thereby to operate said typing member; a manually operable shift key; means responsive to depression of said shift key for effecting connection of said first actuator with said power driven member whereby said first actuator will be power operated to shift said shift element; a manually operable second key; means responsive to depression of said second key for effecting connection of said second actuator with said power driven member whereby said second actuator will be power operated to operate said typing member; a one-way-acting connection for transmitting force from said second key to said shift key for thereby depressing said shift key concomitantly with depression of said second key when the latter is depressed manually, said one-way-acting connection being incapable of transmitting force from said shift key to said second key; a third key; means responsive to depression of said third key for effecting connection of said second actuator with said power driven member independently of operation of said second key and irrespective of the operated or non-operated condition of said shift key and said shift element; and another type character on said typing member effective for typing when only said third key has been depressed.

31. In a power operated typewriter or like

machine, a case shift element; a typing member having a type character thereon effective for typing only when said element is in shifted position; a power driven member; a first actuator operatively connected to said case shift element and normally being disconnected from said power driven member but being connectable therewith for being driven thereby to move said element to shifted position; a second actuator operatively connected to said typing member and normally being disconnected from said power driven member but being connectable therewith for being driven thereby to operate said typing member; a shift key; means responsive to depression of said shift key for effecting connection of said first actuator with said power driven member whereby said first actuator will be power operated to shift said shift element; means controlled by said shift key and effective as long as said shift key is held depressed for maintaining said shift element in shifted position; a second key; means responsive to depression of said second key for effecting repeated connection of said second actuator with

5 said power driven member whereby said second actuator will be power operated repeatedly to operate said typing member; a one-way-acting connection for transmitting depressing movement from said second key to said shift key but not from said shift key to said second key; a third key; and means responsive to depression of said third key for effecting a single operative connection of said second actuator with said power driven member independently of operation of said second key.
